UNITED STATES PATENT OFFICE

ROY LINDSEY, OF HOLLYWOOD, CALIFORNIA

APPARATUS AND METHOD OF CASTING SELF-HARDENING MATERIALS

Application filed December 3, 1928. Serial No. 323,371.

This invention relates to improvements in an apparatus and method of casting self hardening materials.

Heretofore it has been customary to cast long articles such as, for example, cast iron pipe and the like in a vertical position. The mold is first formed with the gate or sprue leading from the top of the mold to the bottom and entering the space which forms the cast article at its bottom. The molten metal flowing down through the gate or sprue enters the space and gradually fills it, thus forming the completed cast article. Such a method which is well known, is disadvantageous in that the length of the article is limited. The molten metal flowing against the cold sand or mold material quickly cools and unless elaborate precautions are taken the height of the article is limited by virtue of the fact that the molten metal will cool and harden before it reaches the top of the mold.

It is an object of this invention to provide a novel apparatus and method of casting self hardening materials which is advantageous in that the length or height and thickness of the article may be of any size, that is, unlimited.

Another object of the invention is to provide a cheap, simple and durable construction and method for casting self hardening materials which is highly desirable in forming rough castings such as cast iron rods, columns or pipe.

A further object of the invention is to provide an apparatus and method having the above mentioned characteristics and which is adapted to simultaneously cast a plurality of articles or simultaneously cast a plurality of various kinds of self hardening materials.

With the foregoing and other objects in view which will be made manifest in the following detailed description and specifically pointed out in the appended claims reference is had to the accompanying drawings for an illustrative embodiment of the invention, wherein:

Fig. 1 is a vertical section through the improved apparatus illustrating the apparatus at the starting position in forming the molded article.

Fig. 2 is a view similar to Fig. 1 illustrating the apparatus at the finished position forming the article.

Fig. 3 is a perspective view of the article formed. 55

Fig. 4 is a vertical section through an apparatus of slightly modified construction while the article is being formed and illustrates the manner in which two or more different kinds of self hardening materials are being cast.

Fig. 5 is a bottom plan view of the forming device used in the apparatus shown in Fig. 4.

Fig. 6 is a view in side elevation of the same. 65

Referring to the accompanying drawings wherein similar reference characters designate similar parts throughout, the improved apparatus consists of a suitable base 10 on which a cylinder 11 is mounted in an upright position. The cylinder 11 constitutes the flask of the mold forming the sides thereof. The bottom of the flask is provided by a table 12 which may be considered a form of elevator adapted to be raised and lowered by the vertical rod 13 which extends through the aperture 14 in the base 10. This rod may be raised and lowered by any suitable mechanism not shown, such as, for example, a hydraulically operated piston or equivalent mechanical construction. At the top of the cylinder 11 there is a suitable hopper 15. A forming device 16 is suspended over the top of the flask by means of the suspending means 85 17. This forming device which is used in forming the article shown in Fig. 3 is circular in form and is inverted U-shaped in section, having an open bottom. The hardening material which is to be cast is supplied to the forming device through a suitable conduit or gate 18. The sand or other mold material is adapted to be fed into the flask and sprinkled over the top of the forming device within the hopper 15 such as by a movable chute 19. 90

The operation of the apparatus is as follows: The table 12 is elevated by the rod 13 to its uppermost position shown in Fig. 1 and some sand is sprinkled in the hopper 100

over the forming device to approximately the level of the top of the forming device. The self hardening material is then fed to the interior of the forming device. If the material to be cast is cold and will become set, such as cement or concrete the forming device 16 may be made of any suitable material. If the material to be cast is in a molten condition such as cast iron or other molten metal the forming device 16 is preferably made of a heat resisting refractory material such as for example, porcelain, fire clay or the like. The table 12 is then gradually lowered, the supply of molten material in the forming device being kept constant. As the table lowers the sand or other mold material is gradually sprinkled over the top of the forming device in the hopper 15 so that it will be kept on a level approximately even with the top of the forming device. The lowering of the table 12 causes relative movement to take place between the sand and the forming device and as the self hardening material flows or is fed out of the bottom of the forming device it expands against the walls of the sand mold and core which walls are formed by the sand becoming packed and formed by the exterior surfaces of the forming device 16. The table 12 is continually lowered to the bottom of the cylinder 11 until it reaches the position shown in Fig. 2 just preceding which the supply of self hardening material is cut off and the supply of sand fed to the mold through chute 19 is stopped. As soon as the self hardening material has cooled or has become set the cylinder 11 can be removed and the sand shaken out producing the cylinder indicated at 20 which will be a section of cast iron pipe if cast iron is used as a self hardening material. It will be appreciated that by the improved method the section of cast iron pipe is gradually formed from the bottom to the top and that the molten metal is always supplied to the mold in a hot fluid state. By the improved method the length of the section of pipe which can be formed is unlimited, the only limitation being the length or height to which the cylinder 11 might be built and the distance through which it is possible to lower the table 12.

In Figs. 4, 5 and 6 a modification is disclosed wherein two different kinds of self hardening materials are being cast simultaneously. In this construction the forming device 16¹ is circular in form and is of an inverted W shape. One kind of self hardening material is supplied through the gate or conduit 18^a and another kind of self hardening material is supplied through gate or conduit 18^b. The table 12 is lowered in the same manner as previously described and the sand is supplied to the mold as before through the chute 19. Both forms of self hardening materials will thus be cast together simultaneously and side by side so that this form

of construction can be advantageously employed in forming a lined or a coated section of pipe. If desired the two inverted forming devices which are shown integral in Fig. 4 could be separated so that during a single casting operation two or more sections of pipe can be cast simultaneously, one within the other with a wall of sand or mold material disposed between them, keeping them separated while cooling or becoming hard. 70

From the above described construction of the apparatus and method it will be appreciated that a novel and advantageous apparatus and method for casting self hardening materials is provided which can be very advantageously employed in casting long articles such as long sections of pipe, columns or any article which should be of considerable length. The shapes given to the articles need not be cylindrical as shown in Fig. 80 3 but may be flat as in forming long cast iron plates or curved. The particular shape of the article merely depends upon the shape given to the forming device 16 which feeds the fluid material to the mold. The improved method and apparatus enables an article to be cast without requiring gates or sprues and risers. Gates, sprues and risers require a lot of additional material to be used in supplying the molten material to the interior of the mold and these parts must later be cut off and re-melted. By eliminating these in the improved method and apparatus a more efficient method of casting is thus provided. 90

While the invention has been shown and described as casting the article in a vertical position it will be readily understood that the article may be cast in various other positions if found desirable. 100

Various changes may be made in the details of construction and in the method of casting without departing from the spirit or scope of the invention as defined by the appended claims. 105

I claim:

1. The method of casting self hardening materials which comprises simultaneously forming the mold and supplying it with the self hardening material to be cast. 110
2. The method of casting self hardening materials which comprises simultaneously feeding the material to be cast and the mold material into a flask, and lowering the bottom of the mold. 115
3. The method of casting self hardening materials which comprises feeding the material in fluid form into a flask through a forming device, and simultaneously feeding mold material into the flask about the forming device and causing relative movement to take place between the forming device and the fed materials. 120
4. The method of casting self hardening materials which comprises simultaneously forming the mold and supplying it with a 125

plurality of self hardening materials to be cast.

5. The method of casting self hardening materials which comprises simultaneously feeding a plurality of materials to be cast and the mold material into a flask, and lowering the bottom of the mold.

6. The method of casting self hardening materials which comprises feeding a plurality of materials in fluid form into a flask through a forming device and simultaneously feeding mold material into the flask about the forming device and causing relative movement to take place between the forming device and the fed materials.

15. 7. An apparatus for casting self hardening materials comprising means providing a flask in which the mold material is adapted to be placed, means for feeding the self hardening material into the flask in the desired shape and means for causing relative movement to take place between the feeding means and the mold material supplied to the flask.

25. 8. An apparatus for casting self hardening materials comprising means providing a flask in which the mold material is adapted to be placed, means for feeding the self hardening material into the flask in the desired shape, and means for lowering the bottom of the mold as the self hardening material and mold material are fed into the flask.

35. 9. The method of casting self hardening materials in tubular form which comprises discharging the material through an annular forming device, and causing the forming device to shape the core and mold.

40. 10. The method of casting self hardening materials into tubular form which comprises simultaneously forming a core and mold from one end toward the other, and filling the space between the core and mold as it is being formed.

45. In testimony whereof I have signed my name to this specification.

ROY LINDSEY.
